UNITED STATES PATENT OFFICE

HARLEY H. CUSHMAN, OF LODI, WISCONSIN

ELECTRICAL LIQUID HEATER

Application filed January 15, 1930. Serial No. 420,931.

This invention appertains to new and useful improvements in electrical heaters, and more particularly to a heater of the immersion type.

5 The principal object of this invention is to provide a portable liquid heater which is capable of being disposed within a volume of water for the purpose of heating the same.

Another important object of the invention 10 is to provide an electric water heater, wherein the heating element is thoroughly protected from the counter-action of the liquid in which the heater is placed.

15 Other important objects and advantages of the invention will become more apparent to the reader after considering the invention as described and claimed hereinafter.

In the drawings:—

Figure 1 represents a top plan view of the 20 novel heating device.

Fig. 2 represents a longitudinal sectional view through the heater.

Fig. 3 represents a cross sectional view of the device.

25 Fig. 4 represents an enlarged fragmentary horizontal sectional view of the heating unit.

Fig. 5 represents a plan view and diagrammatic view of the heating elements and their connections.

30 Fig. 6 is a perspective view of the heater.

Fig. 7 represents a side elevational view of the heater.

Fig. 8 represents a fragmentary sectional view of the conductor cable connection with 35 the heater.

Fig. 9 represents a fragmentary side elevational view of one of the end walls.

Referring to the drawings, wherein like 40 numerals designate like parts, it can be seen that the novel unit is constructed of a pair of end walls 6 and 6, the end walls 6 being provided with a rectangular shaped opening 7.

These end walls 6—6 are connected by the upper and lower walls 8 and 9 respectively, and connecting the longitudinal edge portions of these walls 8 and 9, at their intermediate portions, are the posts 10—10, and these are provided with two pairs of inwardly disposed lugs 11 for supporting the intermediate portions of the rectangular-shaped 50

shells 12—12, which enclose the cores 13 on which the heating elements 14 are wound.

Each of these cores 13 has its longitudinal edge portion provided with notches 15, through which the heating element 14 is trained, and with intermediate pairs of openings 16 through which the heating element is further trained. The ends of the heating element of each core, are disposed through the openings 17 and are connected to the connectors or binding members 18—18.

The members 18—18 are located in longitudinally spaced relation on the di-electric block 19. This block 19 is of semi-circular shape in cross section and engages against the plate 20.

It will be noted that the heating elements 14 are thoroughly insulated from the shells 12 by linings 12' of some suitable di-electric material.

As is clearly shown in Fig. 9, a lug 21 projects inwardly for supporting the upper shell 12, so that the upper shell is maintained on a horizontal plane. The lower shell rests on the lower longitudinal edge of the end wall 6 and the said opening 7.

A plate 22 is secured by a screw 23 to the end wall 6 and this plate 22 is open at its intermediate portion, and from the edge portion of this opening, projects the hood 24, which hood 75 is semi-circular in cross section, to accommodate the block 19, in substantially the manner as shown in Fig. 2.

The hood 24 is provided with an outwardly disposed inter-threaded nipple 25, through 85 which the conductor 26 leads to connect with the connectors 18—18. This conductor 25 is disposed through the jamb nut, which nut 27 is engaged within the nipple 25 to compress the packing 28.

A shield of tubular construction and noted by the numeral 29 is disposed over the conductor 26 and nipple 25 is secured to the conductor 26 by a split clamp 30.

It can thus be seen that when the device is assembled in the manner clearly shown in the drawings, it can be easily conveyed from one place to another for use and it will be particularly noted, that the heating elements are protected against the liquid without sac- 95

rificing any of the valuable heating surface, or heat developed.

A bore 28' extends through the nipple 25 and is enlarged at one end to provide a valve 5 chamber 29' within which the valve elements 36 operate. A screw plug 37 with a vent therethrough closes the enlarged portion of the bore to prevent displacement of the valve element 36. This valve permits air to escape 10 from the shells when the same is expanded by the heat from the heating elements and then when the current is turned off, the valve will close and prevent air from entering the shell so that a partial vacuum is produced in the valve whereby when the current is turned on again, the elements will quickly become hot and transmit their heat to the water in which the device is placed.

Attention is called to the fact that the heating elements are in close contact with the insulating 12' and that these linings are in close contact with the shells so that the heat from the elements is quickly transmitted through the water.

Furthermore, while the foregoing description specifically sets forth the invention, it is to be understood that numerous changes in the shape, size, and materials may be resorted to without departing from the spirit 25 and scope of the invention as claimed herein-after.

Having thus described my invention, what I claim as new is:—

1. A heater of the class described comprising a frame, a shell carried thereby and having its side portions spaced from the frame, a hood attached to one end of the frame and enclosing one end of the shell, the other end of the shell being closed, a heating element 35 in the shell, a lining of non-conducting material surrounding the element and in close contact therewith, and said lining also contacting the inner wall of the shell, a conductor for the heating element passing through the 40 hood, a nipple on the hood through which the conductors pass, a tube connected with the nipple, through which the conductors pass, and means for connecting the hood to the frame and shell, the nipple to the hood and 45 the tube to the nipple in a water proof manner.

2. An immersion heater of the class described comprising a frame having openings therein, a shell supported in the frame and 55 having sides spaced from the frame, one end of the shell being closed, a hood connected with one end of the frame and in communication with the opposite end of the shell, a nipple connected with the hood, a tube connected with the nipple, a heating element in 60 the shell, a lining of non-conducting material placed between the heating element and the shell and in close contact with both conductors for the elements passing through the 65 hood, the nipple and the tube, said nipple

having an air passage therein connecting the shell with the tube, and an outwardly opening check valve in the passage for permitting air to escape from the shell and preventing air from entering the shell.

3. An immersion heater of the class described comprising a casing-like frame having openings therein, a number of shells located within the frame, and spaced from each other and from the walls of the frame, said shells extending parallel to the side walls of the frame, and being of rectangular shape in cross section, one end of each shell being closed, a hood connected with one end of the frame having communication with the other end of each shell, an electric heating element in each shell and insulated therefrom, a tubular member connected with the hood in a liquid-tight manner, and the hood being connected with the frame in a liquid-proof manner, conductors connected with the heating elements, passing through the hood and tubular member, and valve means for permitting air to escape from the shells into the tubular member, but preventing air from passing from the tubular member into the shells.

In testimony whereof I affix my signature.

HARLEY H. CUSHMAN.
